UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

REWINDING DEVICE FOR LOOM LET-OFFS.

Application filed July 27, 1925. Serial No. 43,569.

To all whom it may concern:

Be it known that I, WALTER H. WAKEFIELD, a citizen of the United States, residing at Worcester, in the county of Worcester and State of Massachusetts, have invented a new and useful Rewinding Device for Loom Let-Offs, of which the following is a specification.

This invention relates to improvements in loom let-offs and more particularly to means for rewinding the warp for the purpose of "letting back" the fabric after a "pick out."

It occasionally happens that a faulty pick of filling will be woven into the cloth without being noticed immediately by the weaver but where perfect cloth is being woven these mispicks must be taken out by reversing the weaving operations to pick out all picks laid after the mispick occurred. It is desirable that the original tension on the warp be restored after the pick out and it is the general object of my invention to provide mechanism which will move the warp back under the same tension that it was under before the pick out occurred.

It is a further object of my invention to provide such mechanism with an adjustment readily accessible from the front of the loom, the adjustment operating on the tension whether the same is acting in its normal capacity or to reverse the warp.

With these and other objects which will appear as the description proceeds, my invention resides in the combination and arrangement of parts hereinafter described and set forth in the claims.

In the accompanying drawings wherein I have shown two forms of my invention as applied to the friction drum of a loom operating in conjunction with a creel,

Fig. 1 is a side elevation of the loom having the preferred form of my invention applied thereto,

Fig. 2 is an enlarged front elevation looking in the direction of arrow 2, Fig. 1,

Fig. 3 is a vertical section on line 3—3 of Fig. 2 on an enlarged scale,

Fig. 4 is a view similar to Fig. 2 but showing a modified form of my invention, and

Fig. 5 is an enlarged vertical section on line 5—5 of Fig. 4.

My invention is more particularly appli-

cable to looms for weaving duck, such looms having the warp supply derived either from a warp beam carried on the loom or from a creel disposed to the rear of the loom. Although my invention is applicable to either source of warp delivery, I have shown the same herein as associated with a drum such as is used with a creel. Referring to Figs. 1, 2, and 3 it will be seen that I have provided a loom frame 10 at the rear of which is a friction drum or warp delivery means 11 pivotally mounted thereon as at 12. Secured rigidly to the drum 11 is a bevel gear 13 which meshes with a bevel pinion 14 carried at the rear end of a shaft 15 loosely mounted in bearings 16 secured to the loom frame. 55

The forward end of the shaft 15 is reduced as at 17 to define a shoulder 18, said reduced portion having keyed thereto a friction disk 19 provided with a friction surface 20, such as leather. The disk 19 rotates with the shaft 15 and is held against motion along the shaft to the right as shown in Fig. 3 by engagement with the shoulder 18. Adapted to coact with the disk 19 is a gear 21 having a friction face 22 which is 60

normally pressed against the leather surface 20 by coil spring 23 lying between the gear 21 and a nut 24 threaded on the forward end of the reduced portion 17. Said nut is held 65

in position by a second check nut 25 and both of said nuts may be provided with 70

convenient handles 26 by means of which they 75

may be easily manipulated by the weaver.

The gear 21 meshes with a pinion 27 fastened to a stub shaft 28 loosely mounted on 80

a bearing block 29 which is secured to the loom frame. The forward end of said stub shaft has secured thereto a hand wheel 30

the hub 31 of which is provided with a pair of spaced ears 32 between which is normally 85

located the finger 33 of a weighted lever 34. Said lever 34 is pivoted as at 35 to the bearing block 29 so as to be held against motion 90

transverse of the stub shaft 28.

Under normal conditions the weighted 95

lever 34 is in the full line position shown in Fig. 1 with the locking finger 33 between the ears 32 so that pinion 27 is held against rotation.

Gear 21 meshing with the pinion 27 is therefore held against rotation to resist frictionally the rotation of disk 19. It is to be 100

understood that the latter moves with the drum 11, the retardation of the rotation of

105

the drum being effected through the frictional contact between the faces 20 and 22. Adjustment of the friction may be accomplished by means of nuts 24 and 25 acting on spring 23. At the time of pick out the weighted lever 34 is thrown to the dotted line position shown in Fig. 1, thus unlocking the pinion 27 and gear 21 to permit rotation of the hand wheel 30 in the reverse direction to cause rotation of the friction face 22. The disk 19 will therefore be rotated in reverse direction to cause the drum 11 to move backwardly through the bevel gear and pinion 13 and 14, respectively. It will be noted that no greater force can be brought to bear upon the reversing of the drum than that which can be transmitted by the friction and that the friction during the pick out is the same as that which prevails during normal weaving. When the cloth has been moved back far enough the weighted lever 34 will be returned to its position between the lugs 32, additional movement of the hand wheel to bring said lugs into operative position with respect to the weighted lever occurring without placing undue strain upon the warps.

The modified form of the invention shown in Figs. 4 and 5 differs from the preferred form principally in the type of friction employed, a flexible band friction being substituted for the face friction shown in the preferred form. The shaft 15 has keyed thereto a drum 40 having a cylindrical friction face 41 which contacts with the leather portion 42 of a flexible friction band 43. As shown in Fig. 4 said band is anchored at one end to a fixed stud 44 carried by a plate 45 and has the other end connected by means of a screw and wing nut 46 to a lug 47 also carried by the plate 45.

Said plate 45 is riveted or otherwise secured to a gear 48 meshing with the pinion 27 as in the preferred form of the invention. The operation of the modified form of the invention is substantially the same as that for the preferred form, adjustment of the friction being obtained through the screw and wing nut 46 which is located at the front of the loom where it is readily accessible to the weaver.

From the foregoing it will be seen that I have provided a loom let-back so arranged that the same may be reversed at the time of pick out to cause the warp to be moved backwardly by means of the same friction which normally resists its forward movement, the means for accomplishing this result including two friction members one of which is normally stationary and adjustable and the other being secured to some part which moves with the warp delivery.

Having thus described my invention it will be apparent that changes and modifications may be made therein by those skilled

in the art without departing from the spirit and scope of the invention, and I do not wish to be limited to the details herein disclosed but what I claim is:

1. In a let-off mechanism for a loom having a warp delivery means, a pair of coacting friction elements to resist movement of the warp delivery means, one of said elements being operatively connected to and moving with the delivery means, a lock to hold the other element normally stationary but movable to release said second element, and means to reverse the second named element when the lock is moved to releasing position to cause a reverse movement of the warp delivery means, the contacting portions of the friction elements being intermediate the warp delivery means and the means to reverse the second element. 70

2. In a let-off mechanism for a loom having a warp delivery means at the rear thereof, a normally moving friction element near the front of the loom, connections between the warp delivery means and said element to cause said means and element to move together, a second normally stationary friction element to coact with the first element to retard movement of the warp delivery means, a lock to hold the second element normally stationary but movable to release said second element, and means to move the second named element when unlocked to cause a reverse movement of the first named element and the warp delivery means. 85

3. In a let-off mechanism for a loom having a warp delivery means near the rear of the loom, a friction element adjacent the front of the loom, connections between said element and the warp delivery means to cause said element and means to move together, a second friction element coacting with the first named element to retard movement of the warp delivery means, a lock to hold the second friction element normally stationary but movable to release said second element, and means to move said second element to impart motion to the warp delivery means through the first named element. 95

4. In a let-off mechanism for a loom having a warp delivery means, a friction element adjacent the front of the loom, connections between said element and the warp delivery means to cause said element and means to move together, a second friction element coacting with the first named element to retard movement of the warp delivery means, a lock to hold the second friction element normally stationary but movable to release said second element, means to move said second element to impart motion to the warp delivery means through the first named element, and means accessible from the front of the loom to vary the friction between said elements, said adjustment being maintained when the second 105

named element is moved to cause reverse movement of the means.

5. In a let-off mechanism for a loom having a warp delivery means, a shaft having operative contact with the warp delivery means extending toward the front of the loom, a friction element rigid with respect to the shaft and movable with the warp delivery means, a second friction element loose with respect to the shaft, and a lock to hold the second friction element normally stationary but movable to release the second named element, the latter being movable when released to impart reverse motion to the shaft and warp delivery means through the first named element.

6. In a let-off mechanism for a loom having a warp delivery means, a shaft having operative contact with the warp delivery means extending toward the front of the loom, a friction element rigid with respect to the shaft and movable with the warp delivery means, a second friction element loose with respect to the shaft, a lock to hold the second friction element normally stationary but movable to release the second named element, the latter being movable when released to impart reverse motion to the shaft and delivery means through the first named element, and means readily accessible from the front of the loom to adjust the friction between said elements.

7. In a let-off mechanism for a loom having a frame and warp delivery means supported thereby, a shaft extending from the warp delivery means to the front of the loom, geared connections between the shaft and the means, a friction element rigid with respect to the shaft, a second friction element loose with respect to the shaft and coacting with the first named element, and a locking lever pivoted to the frame and normally holding the second named element against movement but movable to release

said second named element, the latter when released being movable to reverse the direction of the shaft, gearing and means through the first named friction element.

8. In a let-off mechanism for a loom having a frame and a warp delivery means supported thereby, a shaft extending from the warp delivery means to the front of the loom, geared connections between the shaft and the means, a friction element rigid with respect to the shaft, a second friction element coacting with the first named element, a locking lever pivoted to the frame and normally holding the second named element against movement but movable to release said second named element, the latter when released being movable to reverse the direction of the shaft, gearing and means through the first named friction element, and readily adjustable means accessible from the front of the loom to vary the friction between the elements.

9. In a let-off mechanism for a loom having a frame and a warp delivery means supported thereby, a shaft extending from the means toward the front of the loom, geared connections between the shaft and the means, a friction element rigid with respect to the shaft, a second friction element coacting with the first named element and loose with respect to the shaft, a gear movable with the second named element, a pinion meshing with the gear, a hand wheel for the pinion, and a lock normally holding said pinion, gear and second named element stationary but movable to release the same, said second named element being movable by means of the hand wheel and pinion when released to impart reverse motion to the first named element, shaft and warp delivery means through the first named element.

In testimony whereof I have hereunto affixed my signature.

WALTER H. WAKEFIELD.
